(57) **CLAIM**

The ornamental design for a drain, as shown and described.

DESCRIPTION

FIG. 1 is a perspective view of the drain; and, FIG. 2 is a cross sectional view along the line 2-2 in FIG. 1. The broken lines of the drain are for the purpose of illustrating portions of the article and form no part of the claimed design.

1 Claim, 2 Drawing Sheets

FIG. 1

FIG. 2
